UNITED STATES PATENT OFFICE

2,249,702

PROCESS OF REFINING GLYCERIDE OILS
AND FATS

Benjamin Clayton, Houston, Tex., assignor to Refining, Inc., Reno, Nev., a corporation of Nevada

Application December 16, 1939, Serial No. 309,674

20 Claims. (Cl. 260—425)

This invention relates to the refining of glyceride oils and fats, and more particularly to the employment of high temperature treatment of the materials in the refining process.

In the alkali refining of glyceride oils (the term "oil" will be herein employed as being generic to both oils and fats except where the context indicates otherwise), caustic alkalies, particularly caustic soda, have been employed in excess as the neutralizing agent. Caustic alkalies almost instantly neutralizes the free fatty acids in the oil, and no substantial excess is required for neutralization. However, a considerable excess of caustic soda over that necessary to neutralize the free fatty acids has ordinarily been employed in order to reduce the color of the oil and produce a separable soap stock. The excess attacks the neutral oil, causing refining losses due to saponification thereof. For this reason the temperatures in such refining processes have been maintained as low as possible consistent with effective separation of the resulting soap stock from the oil. Even so, the entrainment of neutral oil in the soap stock in batch settling operations has been excessive, representing a major economic loss, and even in continuous processes involving proper conditioning of the mixture and centrifugal separation, a considerable amount of neutral oil has been lost with the soap stock.

The present process is particularly useful in the alkali refining of glyceride oils with non-saponifying alkalies. Such non-saponifying alkalies, of which the alkali metal salts of weak acids are the most common examples, do not saponify neutral oil, and losses due to saponification of neutral oil are eliminated. However, non-saponifying alkalies have not been commercially employed for alkali refining prior to the development leading up to the present application and disclosed in certain of my copending applications hereinafter referred to, although attempts have been made for many years to use the same in refining processes. Among the various reasons for failure of such prior processes are the slowness of the neutralizing reactions; inability to sufficiently neutralize the oil for edible purposes, i. e., reducing its free fatty acid content to below 0.05 and preferably below 0.03%; the inseparable nature of the soap stock obtained; and the lack of color reduction of the oil.

Soda ash is the cheapest and most available of the non-saponifying alkalies, and many attempts have been made to employ this material as a refining reagent. Soda ash has the further disadvantage that large amounts of carbon di-

oxide tend to form during neutralization. This gas formation resulted in violent foaming of the materials during batch neutralizing reactions and, by occlusion of the gas in the soap stock, lightened the same so as to render settling of the soap stock impractical. Attempts have been made to employ dry soda ash as the neutralizing agent or to dry the mixture of oil and soap stock to permit filtering the soap stock from the oil. These processes failed, because a sufficiently neutral oil was not obtained with dry soda ash, and because the losses due to entrainment of oil in the filter bed were excessive.

In my copending applications Serial Nos. 259,502, 265,030 and 296,685, filed March 3, 1939, March 30, 1939 and September 26, 1939, respectively, I have shown how soda ash as well as other non-saponifying alkalies can be employed to successfully refine glyceride oils and fats, for example, by using large excesses thereof or separating the resulting soap stock from the oil in the presence of relatively large amounts of soap stock weighting agents. The present invention is a continuation-in-part of the above mentioned applications and is directed to high temperature treatment of the materials in the process, and particularly to high temperature separation of the foots from the oil. In accordance with the present invention, the amount of soda ash or other non-saponifying reagent necessary for neutralization and effective separation, or the amount of weighting agent present during separation, is markedly reduced. Effective color reduction is accomplished in addition to effective neutralization and separation, so that a refined oil of low color is produced with almost the theoretical minimum losses. Since the oil is subjected to the high temperatures for short periods of time only, the oil is not damaged by the high temperatures.

It is, therefore, an object of the invention to provide a process of refining glyceride oils and fats in which separation of the foots from the oil is accomplished by a difference in specific gravity at high temperatures.

Another object of the present invention is to provide an improved process of refining glyceride oils and fats in which non-saponifying neutralizing agents are employed.

Another object of the invention is to provide a process of refining glyceride oils and fats in which non-saponifying alkalies are employed in minimum amounts to produce refined oils suitable for edible purposes and of reduced color.

Another object of the invention is to provide

a continuous process of refining glyceride oils and fats in which the materials are subjected to high temperatures during the process in order to more effectively reduce color and improve the separation of the soap stock from the oil.

Another object of the invention is to provide a continuous process of refining glyceride oils and fats in which the fats are centrifugally separated from the oil under pressure and at elevated temperatures.

A still further object of the invention is to provide a process of refining glyceride oils and fats in which minimum amounts of soda ash are employed to produce neutral oils and in which refining losses are minimized.

Other objects and advantages of the invention will appear in the following description of the preferred embodiments thereof made in connection with the attached drawing, of which:

Figure 1 is a schematic diagram of an apparatus suitable for carrying out the process of the present invention; and

Figure 2 is a similar diagram of a modified apparatus.

The process will be first described with reference to the alkali refining of glyceride oils with non-saponifying neutralizing reagents to produce neutralized edible oils. Referring to the drawing: 10 indicates a tank constituting a source of supply for the glyceride oil and 11 indicates a similar tank for neutralizing reagent. Oil may be withdrawn from the tank 10 by means of a pump 12 and delivered through a meter 13 and a heating coil 14 to a flow mixer 15. Neutralizing reagent may be withdrawn from the tank 11 by means of a pump 16 and delivered through a proportioning cylinder 17 and a heating coil 18 to the mixer 15. The meter 13 and proportioning cylinder 17 constitute a proportioning device for insuring that accurately proportioned streams of oil and reagent are delivered to the mixer 15. The meter 13 may be of any desired type, but is preferably a positive displacement meter, and is employed to actuate a valve (not shown) for controlling the admission and exhaust of the neutralizing reagent from the opposite sides of the cylinder 17 in which is positioned a free piston (not shown) driven by the neutralizing reagent. The cylinder 17 and associated valve and free piston may be of the well known D valve construction conventionally used in proportioning mechanisms, an example of which is shown in Thurman Patent No. 2,143,062, granted December 27, 1938, and the valve thereof may be actuated by the meter 13 either directly through a connecting rod 19 or through any suitable force amplifying mechanism.

The glyceride and neutralizing reagent are mixed in flow in the mixer 15 under pressure and out of contact with the air, and then delivered through a heating coil 20 into a vapor separating chamber 21. A vacuum may be maintained in the chamber 21 by means of a vacuum pump 22 operating through a condenser 23 and a receiver 24. A relatively high vacuum, i. e., from 27 to 30 inches of mercury, is preferably maintained, although in certain instances a vacuum need not be employed in the vapor separating chamber. The mixture of oil and soap stock is preferably discharged against the walls of the vapor separating chamber 21, for example by nozzles 25. The vapor separating chamber 21 may also be provided with a heating coil 26 and an agitator 27 driven by a motor 28. The vapor separating chamber and associated apparatus serves to re-

move at least a portion of any water or other volatile liquids from the mixture of oil and soap stock and also to remove other vaporizable or gaseous material such as carbon dioxide. In a preferred operation the vapors and gases are substantially all removed from the mixture above the liquid level 28' in the dehydrating chamber, i. e., the vapors and gases are flashed from the mixture. The mixture may be withdrawn from the chamber 21 by means of a pump 29 and delivered through a meter 30 to a flow mixer 31. A weighting and rehydrating agent may be withdrawn from a tank 32, preferably provided with a heating coil 33 and delivered by a pump 34 through a proportioning cylinder 35 and heating coil 36 to the flow mixer 31. The meter 30 and proportioning cylinder 35 may be entirely similar to the meter 13 and proportioning cylinder 17 previously described. The mixture of oil and soap stock may mix with the dehydrating and weighting agent in the mixer 31 and be delivered through a heat exchange coil 37 to a continuous centrifugal separator 38. The soap stock is separated from the oil as the heavy effluent delivered through a spout 39 into a receiver 40, while the neutral oil is delivered as the light effluent through a spout 41 into a receiver 42. The centrifugal separator 38 is preferably of the heated type disclosed in my patent No. 2,100,277, granted November 23, 1937. For high temperature operation, the centrifugal separator may also be of the completely enclosed type capable of operating under pressure so as to prevent liberation of a substantial amount of vapors or gases therein. Since, in the present operation, the oil discharged from the centrifugal 38 may be of high temperature, the receiver 42 is preferably closed except for a vent 43 in order to prevent contact of the heated oil with the atmosphere. If desired, the receiver 40 for the soap stock may also be closed and provided with a vent 43'.

For most oils and fats, the color of the oil is sufficiently reduced in the steps heretofore described, but for highly colored oils or those resistant to color reduction it is sometimes desirable to give the neutral oil a caustic alkali wash in order to still further reduce the color thereof. For this purpose the oil may be withdrawn from the tank 42 by a pump 44 and delivered through a cooling coil 45 and a meter 46 to a flow mixer 47. A color reducing agent, which is ordinarily an aqueous solution of caustic soda, although other materials such as sodium peroxide and equivalent potassium compounds may be employed, is withdrawn from a tank 48 and delivered by a pump 49 through a proportioning cylinder 50 to the mixer 47. The meter 46 and proportioning cylinder 50 may also be entirely similar to the meter 13 and proportioning cylinder 17. The color reducing reaction is preferably carried on at a relatively low temperature obtained by cooling the oil in the cooling coil 45, and the mixture leaving the mixer 47 is preferably given a treating period for reaction in a coil 51. The treating period may be of short duration, and many times may be omitted. However, the temperature found most effective for separating the color impurities from the oil is, in general, higher than the temperature for most effective color reduction reaction. The mixture is therefore preferably passed through a heating coil 52 and delivered to a continuous centrifugal separator 53. The color impurities and any excess color reducing agent are separated from the oil as the heavy effluent and delivered through the

spout 54 into a receiver 55. The oil is delivered as the light effluent through a spout 58 into a receiver 57 and may be withdrawn from the tank 57 by a pump 59 and subjected to any desired further steps such as washing, vacuum drying, bleaching, deodorizing, etc. If the color in the receiver 42 for the neutralized oil from the centrifugal separator 38 is of sufficiently low color, this oil may be directly passed to the subsequent steps above mentioned and the color reduction 10 step omitted.

In the alternative apparatus disclosed in Figure 2, the oil and neutralizing agent may be mixed at relatively low temperature in batch in the mixers 60 and 61. The mixers 60 and 61 are intended to be used alternatively, so that the mixture may be in the process of preparation in one of the mixers while a stream of the completed mixture is being withdrawn from the other. Oil may be introduced into the mixers 60 and 61 through the pipes 62 and 63, respectively, while neutralizing reagent is introduced into the mixers through the pipes 64 and 65, respectively. The tanks 60 and 61 are provided with agitators 66 driven from any suitable source of power through pulleys or gears 67 and are employed to thoroughly mix the neutralizing agent with the oil. After the mixture has been produced, the agitator may be employed to maintain the same substantially uniform while a stream thereof is being withdrawn. The mixture may be withdrawn alternatively from the mixers 60 and 61 by a pump 68 and delivered through a meter 69 and a heating coil 70 to a flow mixer 71. A weighting agent may be withdrawn from a tank 72 which may be provided with a heating coil 73 by a pump 74 and delivered through a proportioning cylinder 75 and a heating coil 76 to the mixer 71. The mixture from the mixer 71 may be delivered through a heating or conditioning coil 77 to a centrifugal separator 78 which may be of the same type as the centrifugal separator 38 of Figure 2. The soap stock is separated as the heavy effluent and may be delivered through a spout 79 into closed receiver 80 provided with a vent 80' and the separated oil is delivered through a spout 81 into a closed receiver 82 provided with a vent 83. The neutralized oil may be removed from the tank 82 by a pump 84 and either delivered to a color reduction step such as shown in Figure 1, or directly to the subsequent steps of washing, drying, bleaching and deodorizing.

Although the continuous mixing step disclosed in Figure 1 is preferred, the batch mixing step of Figure 2 may be employed in the process of Figure 1, and the mixture from the pump 68 of Figure 2 delivered into the heating coil 20 of Figure 1. This modified operation may, therefore, include the steps of batch mixing, partial or complete removal of water or other vaporizable or gaseous materials, rehydration and separation. Furthermore, the continuous mixing step of Figure 1 may be employed in conjunction with the apparatus of Figure 2 by delivering the mixture from the mixer 15 of Figure 1 to the heating coil 70 of Figure 2. Also, in the process exemplified by Figure 2, it is many times unnecessary to add a weighting material to produce effective separation. Thus the mechanism including the tank 72, pump 74, meter 69, proportioning cylinder 75, coil 76, and mixer 71 of Figure 2 may sometimes be omitted or disconnected.

The type of centrifugal separator disclosed in my patent above referred to is particularly 75

susceptible to be converted into a pressure type centrifugal. By merely providing a pressure-tight connection between the rotating bowl and the stationary inlet pipe, it has been found that the resistance to discharge of oil and foots, through their respective discharge ports enables considerable pressure to be imposed upon the materials in the separator by delivering the mixture through the inlet pipe under pressure. Furthermore, the discharge ports referred to may be throttled or the discharge pans of the separator can be made pressure tight and the discharge openings therefrom restricted so as to enable any desired pressure to be maintained in the separator. The arrangement for heating the bowl of the separator may also be employed for imparting to the mixture and particularly the foots being separated, a portion of the heat necessary for the high temperatures of separation contemplated in the present invention. However, any suitable type of pressure centrifugal may be employed for carrying out the present process.

In the preferred alkali refining process carried out in the apparatus of Figure 1, the glyceride may be any vegetable, animal or fish oil or fat, and the neutralizing reagent may be any non-volatile, non-saponifying neutralizing reagent. That is to say, practically any of the alkali metal salts having an alkaline reaction such as the carbonates, phosphates, silicates, etc. of sodium or potassium. Since soda ash is the cheapest and most available of these reagents, the process will be particularly described with reference thereto. Furthermore, soda ash is perhaps the most difficult of the non-saponifying alkalies to employ and will best exemplify the novel nature of the improvement represented by the present invention. A substantial excess of soda ash over that necessary to neutralize the free fatty acids in the oil will ordinarily be employed, not only to insure complete neutralization but to effect color reduction. Thus, an amount of soda ash in at least twice the amount necessary for neutralization will usually be employed, although in some instances in the process of Figure 1 this excess may be smaller, and for an extremely highly colored oil may be considerably larger. It is entirely possible to use caustic alkali in not more than the amount necessary to neutralize the free fatty acids and use soda ash or other non-saponifying alkali to neutralize any remaining free fatty acids and provide an excess. Since soda ash is considerably cheaper than caustic alkali, this expedient will not ordinarily be used, except in the case of extremely high free fatty acid oils. A small amount of sodium or other alkali metal peroxide can be advantageously added along with the soda ash so as to function both as a neutralizing agent and to liberate oxygen. The oxygen aids in reduction of color of the oil in the vapor separating chamber. Other oxygen liberating materials such as hydrogen peroxide may also be employed in conjunction with a neutralizing agent. As an aid in carrying off vaporizable materials, volatile liquids such as any of the volatile alcohols or their esters or oil solvents such as hydrocarbons can be mixed with the refining reagent or oil so as to be present in the mixture entering the vapor separating zone. Such materials can be recovered in the condenser 24 and reused in the process.

As shown in Figure 1, both the glyceride and neutralizing reagent may be preheated in the heating coils 14 and 18, respectively, prior to

mixing, although in most cases substantially all of the heat will be applied after mixing the oil and reagent. If preheating is employed, the preheating temperatures may range from slightly above room temperature to temperatures as high as approximately 500° F. Even if preheating is used, it is many times possible to eliminate the heating coil 18 for the neutralizing reagent, as the amount of neutralizing reagent represents a rather small proportion of the total mixture and the mixing temperature will be relatively high, even though the neutralizing agent is supplied at room temperature. If caustic alkali is employed in conjunction with a non-saponifying alkali, the caustic will react with the fatty acids substantially instantaneously in the mixer 15, even at room temperatures. Non-saponifying alkalies react very slowly and incompletely at low temperatures, but at high preheat temperatures such alkalies rapidly neutralize the free fatty acids. With such high preheat temperatures, the heater coil 20 may be omitted, but in a preferred process the mixing is performed at relatively low temperatures, for example temperatures between 70 and 100° F., and the mixture heated to relatively high temperatures, for example above 200° F., usually between 212 and 500° F. and preferably between 250 and 350° F., in the heating coil 20. At these high temperatures the neutralizing reaction is rapid, even with non-saponifying alkalies, and a substantially completely neutralized oil can be delivered into the dehydrating chamber 21. In a somewhat less desirable operation, the heating coil 20 may be employed to impart only a portion of the heat to the mixture and the remaining heat may be supplied by the heating coil 20 positioned in the vapor separating chamber 21.

It is preferred, however, to supply all or substantially all of the heat in the heating coil 20. The mixing and heating is preferably performed under superatmospheric pressure so that introduction of the mixture into the lower pressure zone of the vapor separating chamber 21 causes substantially all of the water, other vaporizable impurities and gas which it is desired to remove, to be flashed from the mixture. The agitator 27 is employed to maintain a substantially uniform mixture in the vapor separating chamber 21. Vapors and gases are preferably removed from the vapor separating chamber by the condenser 23 and vacuum pump 22. Any condensable material is condensed in the condenser 23 and delivered into the receiver 24 in order to assist in maintaining a vacuum in the vapor separator 21. A relatively high vacuum, for example 28 to 29 inches of mercury, is preferably maintained in the dehydrator 21, although lower vacuums and even atmospheric pressure may in some instances be employed. The vapor separating chamber 21 may not only be employed to remove vaporizable material from the oil and produce a better quality oil, but also may be employed to remove any carbon dioxide which may be formed as a result of employing soda ash or other carbonate for neutralization. It has also been found that complete or partial dehydration of the soap stock followed by rehydration in the mixer 31 modifies the nature of the soap stock to produce more efficient separation than is the case if the dehydrator is omitted as in Figure 2. Also, the color of the oil is further reduced than is the case in the process of Figure 2.

In the practical operation of processes prior to the development leading up to the present inven-

tion, separation temperatures above approximately 160° F. have not been employed. The present invention, however, contemplates high temperature separation of the oil from the soap stock. Such temperatures will ordinarily run materially in excess of 212° F. but may be as low as 250° F. or as high as 500° F. The preferred temperature is in the neighborhood of 300° F., for example between 250 and 350° F. At the lower temperatures in the broad range given a substantially dry soap stock or a soap stock containing very little water will not flow continuously from the centrifugal separator. In such cases the vapor separating chamber can be operated under conditions to leave sufficient water in the mixture for effective separation or a rehydrating agent may be mixed with the dehydrated mixture in the mixer 31. Excess non-saponifying alkali aids materially in forming a separable soap stock. If sufficient excess is mixed with the oil, in the neutralizing mixer 15, the weighting agent may be water alone, although an aqueous solution of an alkali metal salt is preferred. Either alkaline or substantially neutral salts may be employed. For example, soda ash constitutes an excellent weighting agent. Other non-saponifying alkalies such as tri-sodium phosphate, sodium silicate and also substantially neutral salts such as sodium sulfate, as well as equivalent potassium or other alkali metal compounds, may also be employed. Furthermore, soaps, particularly the more liquid soaps such as the sodium or potassium soaps of rosin or naphthenic acids or the potassium salts of fatty acids, aid in separation. It is possible to add these weighting materials with the neutralizing agent in the mixer 15, but, since it is usually necessary to rehydrate the mixture from the dehydrator 21, they are more conveniently added in the mixer 31, and less material need be handled in the dehydrator 21. In the present invention the high temperature of separation contemplated renders the employment of weighting agents less necessary, and in many cases effective separation can be produced with small excesses of soda ash or other non-saponifying alkali as the neutralizing agent with no additional weighting agent. Also, the amount of water necessary for rehydration is reduced over that described in my copending applications above referred to. At the higher temperatures of separation, the invention contemplates the centrifugal separation of dry or substantially dry mixtures as the high temperatures liquefy or at least soften both the gums and the soap. At least a small amount of water aids materially in separation however, for example, from approximately 1/2 to 3% water on the basis of the oil, depending upon the amount of free fatty acids and gums originally present in the oil, produces a mixture in which the water represents approximately 30 to 50% of the soap stock. With this amount of water, the soap is substantially insoluble in the oil even at high temperatures. In general, however, the greater the excess of soda ash or of weighting agent, the more water that is desirably employed. That is to say, water is desirably added in approximately the same weight as the additional soda ash or other weighting agent. Also, the lower the temperature of separation the greater the amount of water desirably present during separation. Thus, the water content may be as high as 10% or higher on the basis of the oil present.

The high temperatures contemplated in the present invention are possible as the oil is subjected to these temperatures for very short periods of time, so that substantially no splitting of the oil occurs. The non-saponifying alkali does not attack the oil as would be the case if an excess of caustic were employed. Furthermore, an excess of caustic at the high temperatures referred to would degenerate or decompose the gums present in the oil and cause the same to be softened to an extent that a substantial portion thereof would be soluble in or at least separate with the oil. Non-saponifying alkalies such as soda ash do not soften the gums to the same extent as caustic soda. That is to say, much larger amounts of non-saponifying alkalies are necessary to produce the same gum softening action. The high temperatures contemplated in the present invention, however, soften the gums and liquefy the soap stock to an extent rendering centrifugal separation extremely efficient even if relatively small excesses of non-saponifying neutralizing reagents are employed. The exact temperature of separation will, therefore, depend upon the nature of the oil being refined and its free fatty acid and gum content, but as stated above, will usually range from 250 to 500° F. and preferably is in the neighborhood of 300° F.

At separation temperatures substantially above 212° F. the water present in the mixture will tend to flash into steam in the centrifugal separator and cause soap stock to remain in the oil. It has been found, however, that separation is not interfered with even at temperatures considerably above 212° F. as the pressure at the zone of separation in a centrifugal separator is several hundred pounds per square inch. With centrifugals having an inlet open to the atmosphere steam will be formed in the inlet portion, if water is present, but this may be prevented by employing enclosed pressure type centrifugals capable of being operated under pressure sufficient to retard the formation of steam, which pressure may range from a few pounds per square inch at the lower temperatures up to several hundred pounds per square inch at the upper pressures.

Since soda ash reacts very slowly, if at all, with free fatty acids at low temperatures, for example room temperature, the soda ash may be mixed with the oil in batch, as shown in Figure 2. Excessive foaming due to the formation of carbon dioxide is avoided, and the mixture may be rapidly heated in the heating coil 70. At elevated temperatures, for example temperatures above 200° F., the neutralizing reaction is quite rapid and the oil is rapidly neutralized in the heating coil 70. The resulting mixture is preferably passed through the second coil 77 to condition the same for separation even if no additional weighting agent is added in the mixer 71. Separation is preferably carried on between temperatures of 250 to 500° F., and this temperature may be attained in the heating coil 77. A pressure centrifugal separator may be employed for separation, if necessary, as discussed with reference to Figure 1. When employing soda ash carbon dioxide may tend to form and interfere with separation. This interference with separation may be prevented in several ways. For example, at least twice as much soda ash is required for neutralization of the free fatty acids may be employed. Sufficient other alkali may be used in the process to combine with any carbon dioxide

which may tend to form so as to form a carbonate. As stated before, even a limited amount of caustic alkalies can be employed without attack on neutral oil. This additional alkali need not be added simultaneously with the carbonate but may be mixed with the oil either before or after the addition of the carbonate. By operating the entire system under pressure, including the centrifugal separators, any carbon dioxide formed may be maintained in solution in water, that is to say, in the form of carbonic acid. When the dehydrator is omitted as in Figure 2, it is ordinarily necessary to employ somewhat more soda ash or other weighting agent during separation. Since no dehydration is employed in the process of Figure 2, volatile non-saponifying agents such as ammonium hydroxide, various amines such as triethanolamine, etc., may be used, as well as the salts of alkali metals having an alkaline reaction. This is particularly true if a pressure centrifugal separator is employed to prevent the production of vapors in the separator.

The process above described materially reduces the color of the oil, but if necessary the oil may be given a color reduction wash. Color reduction reactions with caustic color reducing agents are most effective at relatively low temperatures, for example, temperatures between 70 and 100° F. It is therefore desirable to cool the oil in the cooling coil 45 to a temperature not substantially above 100° F. prior to mixing the color reducing agent therewith. The color reducing agent preferably comprises a caustic soda solution having a concentration of from, for example, between 10 and 30° Bé. The amount necessary for color reduction will vary for different oils, but may be as low as $\frac{1}{10}$ of 1% up to approximately 3%. In many cases it is desirable to provide a short time for color reduction reaction at the low temperature in a treating coil 51. The mixture is then preferably rapidly heated to a temperature between approximately 120 and 160° F. and continuously centrifugally separated in the separator 53. In such a treatment, it has been found that the caustic does not materially attack the oil and that no substantial amount of oil is entrained with the color impurities. Thus, the losses in this portion of the system may be as low at $\frac{1}{10}$ of 1% or lower.

The amount and concentration of the refining reagents employed in the process will vary widely in accordance with the nature of the oil being refined, i. e., the source of the oil, the amount and type of free fatty acids and the amount and type of gums and coloring matter, as well as the temperature of treatment and separation, and the type of refining agent. In general, the more highly colored oils require a greater excess of refining reagent if color reduction is desired. However, the high temperatures minimize the excess required for color reduction and separation. Thus, for producing a neutral oil, amounts of neutralizing reagent from just slightly more, i. e., 5 or 10%, than that theoretically required for reaction with the fatty acids up to excess of several times the theoretical amount may be used. The high temperatures also minimize the amount of water required for neutralization and separation. Thus, very concentrated solutions or even slurries of neutralizing agent are sometimes practicable. Even dry or substantially dry neutralizing agents react with the free fatty acids and precipitate gums and coloring matter with high temperature treatment. At the lower temperatures more dilute solutions of refining reagent

are usually desirable during neutralizing and the presence of substantial amounts of water is desirable during separation.

Even less neutralizing reagent than that required for reaction with the free fatty acids may be employed to produce partial refined oil such as "degummed" or "non-break" oil still containing free fatty acids but useful for many purposes other than for edible products. Also, substantially neutral salts or slightly acid reagents can be employed to precipitate gums either in substantially dry or in aqueous solution to make a "degummed" or "non-break" oil. Even acid refining wherein strong mineral acids are used to render gummy matter separable from the oil can be practiced by the present invention. The high temperature conditions rapidly complete any reactions which take place and render the foots separable in the presence of a minimum amount of refining reagent and water before the oil has been damaged.

A major advantage of the present invention when applied to alkali refining with non-saponifying alkalies is the excellent quality of the soap stock which is produced. The present invention enables a smaller amount of alkali to be employed so that materially less acid is required to release the combined fatty acids. The small amount of water in the foots render them less bulky and more stable against fermentation. Furthermore, at the higher temperatures of separation, the release of the soap stock into atmospheric pressure from a pressure centrifugal causes all or a portion of the water to be vaporized and separated from the soap stock. With non-saponifying alkalies, certain valuable constituents of the gums, for example, the phosphatides present in vegetable oils, are not decomposed to the extent that this occurs in known processes of refining with caustic alkalies. This is particularly true when the temperatures in the process are maintained in the lower portion of the range given, i. e., below approximately 300 or 325° F.

One way of operating the process of the present invention particularly with non-saponifying alkalies such as soda ash, is to mix the refining agent with the oil and partially or substantially completely dehydrate the mixture in the vapor separating zone at relatively low temperatures, for example temperatures between 160 and 250° F., then introducing into the mixture a rehydrating agent which may be either water alone or a solution of soda ash or other non-saponifying alkali, depending upon the amount of refining agent initially added. The rehydrating agent may be at the same temperature, at a lower temperature or a higher temperature than the mixture to which it is added. The latter is advantageous since the rehydrating agent may serve to elevate the temperature of the resultant mixture to condition it for separation. The resultant mixture may also be further added to produce the desired temperature of separation which will usually fall between 250 and 500° F., and preferably between 250 and 350° F. The relatively low temperature of dehydration produces a soap stock in which the gums are more easily rehydrated than is the case where higher temperatures of dehydration are employed. As a result somewhat lower temperatures and less dehydrating agent can be employed during separation while still producing a liquefied soap stock.

The major advantage of the present invention is the savings in refining losses and in costs of

refining agents in alkali refining. With non-saponifying alkalies there is no loss of neutral oil due to saponification thereof. Because of the small amounts of reagents it is possible to employ and the liquid nature of the soap stock, entrainment losses are substantially eliminated so that almost theoretical losses are obtained. Furthermore, highly colored oils are markedly reduced in color and of a quality which requires little if any subsequent treatment, such as deodorizing, bleaching, etc.

While I have disclosed the preferred embodiments of my invention, it is understood that the details may be varied within the scope of the following claims:

What I claim is:

1. The process of refining glyceride oils and fats, which comprises, mixing a refining agent with said glyceride to precipitate foots, and separating said foots from said glyceride by difference in specific gravity at a temperature in excess of 200° F. and below 500° F.

2. The process of refining glyceride oils and fats, which comprises, mixing a refining agent with said glyceride to precipitate foots, and separating said foots from said glyceride by difference in specific gravity at a temperature between approximately 250 and 500° F.

3. The process of refining glyceride oils and fats, which comprises, mixing a refining agent with said glyceride to precipitate foots, and separating said foots from said glyceride by difference in specific gravity at a temperature between approximately 250 and 350° F.

4. The process of refining glyceride oils and fats, which comprises, mixing a refining agent with said glyceride to form a mixture of glyceride and foots, continuously centrifugally separating said foots from said glyceride at a temperature between approximately 250 and 500° F., and maintaining said mixture under sufficient pressure during said separation to prevent liberation of vapors or gases interfering with said separation.

5. The process of refining glyceride oils and fats, which comprises, mixing a refining agent with said glyceride to form a mixture of glyceride and foots, continuously centrifugally separating said foots from said glyceride at a temperature between approximately 250 and 350° F., and maintaining said mixture under sufficient pressure during said separation to prevent liberation of vapors or gases interfering with said separation.

6. The process of refining glyceride oils and fats, which comprises mixing a refining agent with said glyceride and forming a mixture of glyceride and foots containing insufficient water to produce centrifugally separable foots at temperatures of separation below 160° F., and continuously centrifugally separating said foots from said glyceride in a continuous centrifugal separator at a temperature above 200° F. and sufficiently high to cause said foots to continuously flow from said separator.

7. The process of refining glyceride oils and fats, which comprises, mixing a non-saponifying neutralizing agent with said glyceride and forming a mixture of glyceride and soap stock containing insufficient water to produce centrifugally separable soap stock at a temperature below 160° F., and continuously centrifugally separating said soap stock from said glyceride in a continuous centrifugal separator at a temperature above 200° F. and below 500° F. but sufficiently

high to cause said soap stock to continuously flow from said separator.

8. The process of refining glyceride oils and fats, which comprises, mixing a non-saponifying neutralizing agent with said glyceride and forming a mixture of glyceride and soap stock containing insufficient water to produce centrifugally separable soap stock at a temperature below 160° F., and continuously centrifugally separating said soap stock from said glyceride in a continuous centrifugal separator at a temperature between 250 and 500° F.

9. The process of refining glyceride oils and fats, which comprises, mixing soda ash with said glyceride and forming a mixture of glyceride and soap stock containing insufficient water to produce centrifugally separable soap stock at a temperature below 160° F., and continuously centrifugally separating said soap stock from said glyceride in a continuous centrifugal separator at a temperature above 200° F. and sufficiently high to cause said soap stock to continuously flow from said separator.

10. The process of refining glyceride oils and fats, which comprises, mixing a non-saponifying neutralizing agent with said glyceride to form a mixture of glyceride and soap stock, continuously centrifugally separating said soap stock from said glyceride at a temperature between approximately 250 and 500° F., and maintaining said mixture under sufficient pressure during said separation to prevent liberation of vapors or gases interfering with said separation.

11. The process of refining glyceride oils and fats, which comprises, mixing soda ash with said glyceride to form a mixture of glyceride and foots, continuously centrifugally separating said foots from said glyceride at a temperature between approximately 250 and 500° F., and maintaining said mixture under sufficient pressure during said separation to prevent liberation of vapors or gases interfering with said separation.

12. The process of refining glyceride oils and fats containing free fatty acids, which comprises, mixing a non-saponifying neutralizing agent with said glyceride to neutralize said free fatty acids and form a mixture of glyceride and soap stock, continuously centrifugally separating said soap stock from said glyceride at a temperature between approximately 250 and 500° F., and maintaining said mixture under pressure and in stream flow from the point of neutralization of said free fatty acids until separation has been completed.

13. The process of refining glyceride oils and fats containing free fatty acids, which comprises, mixing soda ash with said glyceride to neutralize said free fatty acids and form a mixture of glyceride and soap stock, continuously centrifugally separating said soap stock from said glyceride at a temperature between approxi-

mately 250 and 500° F., and maintaining said mixture under pressure and in stream flow from the point of neutralization of said free fatty acids until separation has been completed.

14. The process of refining glyceride oils and fats, which comprises, mixing a refining agent with said glyceride, heating a flowing stream of the resulting mixture under pressure and out of contact with the air to a temperature between 250 and 500° F., and continuously centrifugally separating the resulting foots from said glyceride at said temperature.

15. The process of refining glyceride oils and fats, which comprises, mixing soda ash with said glyceride, heating a flowing stream of the resulting mixture under pressure and out of contact with the air to a temperature between 250 and 500° F., and continuously centrifugally separating the resulting soap stock from said glyceride at said temperature.

16. The process of refining glyceride oils and fats, which comprises, mixing a refining agent with said glyceride, heating a flowing stream of the resulting mixture under pressure and out of contact with the air to a temperature between 250 and 500° F., subjecting said mixture to a dehydration treatment, and continuously centrifugally separating the resulting foots from said glyceride at said temperature.

17. The process of refining glyceride oils and fats, which comprises, mixing soda ash with said glyceride, heating a flowing stream of the resulting mixture under pressure and out of contact with the air to a temperature between 250 and 500° F., subjecting said mixture to a dehydration treatment, and continuously centrifugally separating the resulting soap stock from said glyceride at a temperature sufficiently high to cause said soap stock to flow continuously from the centrifugal separator employed.

18. The process of refining glyceride oils and fats which comprises: mixing soda ash with said glyceride to form soap stock, conditioning said soap stock for the act of centrifugal separation by the presence of heat sufficient to provide a temperature of said soap stock above 200° F. and sufficient to liquefy the soap stock and separating the thus liquefied soap stock from the refined oil.

19. The process as defined in claim 18 in which the soda ash added during the process is at least several times that required to neutralize the free fatty acids.

20. The process as defined in claim 18 in which the mixture is heated in stream flow to a temperature sufficient to liquefy the soda ash soap stock, thereby to condition the same for centrifugal separation.

BENJAMIN CLAYTON.

CERTIFICATE OF CORRECTION.

Patent No. 2,249,702.

July 15, 1941.

BENJAMIN CLAYTON.

It is hereby certified that error appears in the printed specification of the above numbered patent requiring correction as follows: Page 1, first column, line 45, for the word "reactions" read --reaction--; page 2, second column, line 20, for "dehydrating" read --rehydrating--; line 24, after "effluent" insert --and--; page 5, first column, line 72, for "is" read --as--; and second column, line 49, for "at" read --as--; and that the said Letters Patent should be read with this correction therein that the same may conform to the record of the case in the Patent Office.

Signed and sealed this 23rd day of September, A. D. 1941.

Henry Van Arsdale,
Acting Commissioner of Patents.
